The ornamental design for a mop frame, as shown and described.

DESCRIPTION

FIG. 1 is a top, front, left perspective view of a mop frame showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top, rear, right perspective thereof.

The broken lines in the figures depict a portion of the mop frame that is not part of the claimed design.
